UNITED STATES PATENT OFFICE.

JOHN ARTHUR DRECHSLER, OF HILSDALE, MICHIGAN.

SHOE-RETAINER.

1,392,628.

Specification of Letters Patent.

Patented Oct. 4, 1921.

Application filed March 1, 1919. Serial No. 279,997.

To all whom it may concern:

Be it known that I, JOHN A. DRECHSLER, a citizen of the United States, residing at Hillsdale, in the county of Hillsdale and 5 State of Michigan, have invented certain new and useful Improvements in Shoe-Retainers; and I do hereby declare the following to be a full, clear, and exact description of the invention, such as will enable others 10 skilled in the art to which it appertains to make and use the same.

The invention relates to shoes and consists of means for preventing a low shoe or slipper from drawing away from the foot at the 15 heel.

The object of the invention is to provide a device which will subserve the above stated function and at the same time be easy of application to a shoe without the use of 20 stitches, so that any person who obtains one of the devices embodying the invention may be able to apply it to its place of use.

Referring to the drawing,—

Figure 1 is a side view of a shoe showing 25 one of my devices in position, a part of the shoe being broken away to reveal said device.

Fig. 2 is a plan view of the shoe shown in Fig. 1; and

Fig. 3 is a perspective view showing one 30 of my devices.

The device consists of a body portion of canvas or other suitable material, indicated by the numeral 1, the convex surface of said body portion being provided with a layer 2 35 of suitable gum which when moistened will become adhesive in order that said body portion may be caused to adhere to the inside of the heel portion of the shoe.

The device has tapering ends 3 and is generally curved to conform to the heel portion 40 of the shoe.

Secured to the body portion interiorly at its upper edge is a strip of elastic material 4. This strip may be retained in position 45 by stitches 5 or by other suitable means extending through the upper edge and the two

ends thereof, the lower edge of said strip being unsecured or free. The elasticity of the strip causes it to extend inward at an angle to the heel of the shoe, and thereby 56 to engage the heel of the wearer, so that any tendency of the heel to rise out of the shoe will be met by the restraining influence of the strip.

The strip is sufficiently soft to avoid abrasions or irritations of the foot, but is at the same time strong enough to sustain the weight of the shoe and prevent its movement relative to the foot.

The body portion may be composed of a 60 single layer of canvas, but I prefer to employ two or more layers, the interior of which may be of paper or other fibrous material. These layers are united by stitching extending around the entire margin 65 thereof, and also across the body portion, preferably at two points 6 and 7 which are coincident with the ends of the strip 4.

When the retainer is to be applied to a shoe it will be slightly moistened and properly centered in the heel of the shoe and pressed hard with the fingers until the adhesive becomes sufficiently dry to adhere to the surface of the shoe. Care should be taken to avoid too much moisture or the adhesives will not stick properly.

Having thus described my invention what I claim as new and desire to secure by Letters Patent is:

A shoe retainer comprising a sheet of 80 material adapted to be curved to substantially U-shape, and inserted within the counter portion of a shoe, a yielding strip secured at its upper margin to the upper margin of the sheet, and throughout a portion of its length, the ends of said sheet extending beyond the ends of the yielding strip and affording means for securing the sheet within a shoe.

In testimony whereof, I affix my signature.

JOHN ARTHUR DRECHSLER.
